UNITED STATES PATENT OFFICE.

ALBERT TEICHMANN, OF FÜRSTENWALDE, GERMANY.

SIEVE.

SPECIFICATION forming part of Letters Patent No. 705,717, dated July 29, 1902.

Application filed June 10, 1901. Serial No. 64,032. (No model.)

To all whom it may concern:

Be it known that I, ALBERT TEICHMANN, a subject of the King of Prussia, Emperor of Germany, residing at Fürstenwalde-on-the Spree, in the Kingdom of Prussia and Empire of Germany, have invented new and useful Improvements in Sieves, of which the following is a specification.

My invention relates to sieves for sifting, sorting, bolting, screening, and like apparatus.

Numerous attempts have heretofore been made to replace the silk gauze of sifting and like apparatus by other materials which are cheaper and more durable. Thus the gauze was replaced by sifting-surfaces of celluloid, and trials show that this material forms a substitute which works well; but in practice the use of the same for sifting-machines was checked by its inflammability, the point of ignition being 90° centigrade below that of the silk gauze usually employed. Wire-gauze, perforated plates, perforated skins, and the like were also found to be unsuitable in practice for various reasons.

The object of my invention is to provide a sieve for the above purposes which, first, is cheaper than any heretofore produced; secondly, more durable, safe, and almost fire-proof, and, thirdly, more efficient, as will be further described.

In the accompanying drawings I have illustrated my improved sieve, in which— Figure 1 is a section on the line A B of Fig. 2 and showing the frame to which the sieve is fastened, and Fig. 2 is a plan of the sieve.

Referring now to the drawings for a further description, *b* is a frame, of any suitable make and shape, to which the perforated sheet or sieve of vulcanized fiber *a* is attached by nails *c*. The perforated sheet of vulcanized fiber has many advantages over the materials heretofore enumerated and for the purpose named. For instance, the vulcanized fiber is not affected by either hot or cold water or other moist agents and in this respect

surpasses silk gauze and also the before-mentioned substitutes which have heretofore been employed. Its point of ignition is far higher than that of silk gauze and particularly that of celluloid sieves.

The perforated sheet of vulcanized fiber is satined for the purpose of smoothing its rough surfaces to prevent the material which is to be sifted from adhering to the same and is then used like silk gauze. It is glued, nailed, or otherwise fastened upon the cylindrical or flat frame *b*. The satining, smoothing, or hot-pressing of the vulcanized fiber is accomplished by passing the sheet between highly-polished cylinders, which are heated, or by placing them between polished zinc plates and subjecting them to high pressure, so that the surfaces of the vulcanized fiber sheet are rendered smooth and glossy and the fiber compressed to great density. This satining or hot-pressing of the vulcanized fiber sheets gives them a certain temper, like spring-steel, so that when such sieves are used for sifting flour, &c., by which the sieve is subjected to jerky or vibratory motion, the sheet will first follow the downward direction and then react, so that a double action of the sieve is acquired.

No material heretofore used for sieves of this kind has the properties of reacting in a degree obtained by the use of vulcanized fiber, especially when it is satined or hot-pressed. The manufacture of the sheets of vulcanized fiber is well known and does not form part of this invention; but,

Having thus described the nature and object of my invention, what I claim as new, and desire to secure by Letters Patent, is—

A sieve for sifting and analogous machines, consisting of a hot-pressed perforated sheet of vulcanized fiber, substantially as and for the purposes set forth.

ALBERT TEICHMANN.
